UNITED STATES PATENT OFFICE.

JOHN HARRIS, OF LAKEWOOD, OHIO.

ACETYLENE GENERATOR.

Application filed November 1, 1920. Serial No. 420,943.

To all whom it may concern:

Be it known that I, JOHN HARRIS, a citizen of the United States, residing at Lakewood, in the county of Cuyahoga and State 5 of Ohio, have invented a certain new and useful Improvement in Acetylene Generators, of which the following is a full, clear, and exact description, reference being had to the accompanying drawings.

10 My invention relates to acetylene apparatus, and has for its objects to improve the construction of the means for feeding carbide to the generator; to provide means whereby, when the carbide tank or receptacle 15 is to be filled, the escape of gas into the apartment wherein the generator is located is prevented; and generally to improve the construction of the holder wherein the gas is stored for supply. Generally speaking, 20 the invention may be defined as consisting of the combinations of elements embodied in the claims hereto annexed.

Referring to the drawings, Fig. 1 represents a sectional view of an acetylene apparatus constructed in accordance with my invention,—the lower portion of the generator being shown in elevation;

Figure 2 represents a transverse sectional view taken on the line 2—2 of Fig. 1; Fig. 3 30 represents a side elevation of the cover or hood for the carbide receptacle; and Fig. 4 represents an enlarged sectional view of the valves by which the flow of carbide into the generator is controlled.

35 Describing the parts by reference characters, 1 represents the generator, communicating by a pipe 2 with the holder 3. The generator is provided near the upper portion thereof with a transverse partition 4 having a central opening 5, through which carbide is introduced into the generator through the casing 6. The lower portion of the generator is provided with a floor 7, above the base thereof, said floor sloping downwardly to the 45 outlet 8 through which exhausted material is withdrawn from the generator.

A tube 9 extends downwardly from the partition 4 into the body of the generator, a short distance above the floor 7, and is provided with a spout 10 extending from above the bottom thereof.

50 11 designates one branch of a rod, the upper end of which is connected to a lever 12, pivoted at 13 and having its outer end provided with a rule-joint operating finger 14. The branch 11 extends downwardly and

centrally through the tube 9, through a hole in the bottom thereof, and is connected with the upwardly extending branch 15 by which the valves controlling the flow of carbide to the generator are operated. The branch 15 extends through a guide 16 secured to the wall of the casing 6. Above this guide, it is bent outwardly and upwardly, to provide an upward extension 17 projecting centrally through the valves 18 and 19, which control the supply of carbide to the generator. The upper end of said extension is guided in a sleeve 20 carried by the conical distributor 21, which is supported within and spaced 60 from the bottom of the main receptacle 22 by means of brackets 23. The bottom 24 of the receptacle 22 is inclined downwardly to facilitate the feed of the carbide and is provided with a central opening 25 whereby carbide may be discharged into the auxiliary receptacle 26, which is beneath the receptacle 22, and wholly within the casing 6. The receptacle 26 is also provided with a downwardly inclined bottom 27 having a central 70 opening 28 therein. The extension 17 of the valve rod projects centrally through the openings 25 and 28, as well as through the valves 18 and 19. As will appear more particularly from Fig. 4, the valves are of 80 frusto-conical shape with their bases normally closing the openings 25 and 28. The former valve is connected to the extension 17, as by means of a set screw 29, whereby it may move therewith. The valve 19 is loosely 85 sleeved on the rod 17 and is normally unaffected by the movement thereof. The extension is, however, provided with a projection 30, which is adapted to engage the valve 19 and lift the same when the valve rod has 90 been operated the desired distance.

The upper portion of the generator, above the partition 4, constitutes both a water supply receptacle for the generator proper therebelow and an overflow receptacle whereinto water may be forced from the lower portion of the generator should the pressure of the gas therein become excessive. The pipe 2, which conveys gas into the holder, has one end connected to the partition 4, 105 while the other end terminates in a perforated distributing cylinder 31 in a receptacle 32, which is enclosed within the base 33 of the holder. This receptacle is nearly filled with water whereby the gas discharged 110 through the perforations 31 is washed before passing through the tube 34 into the

bell 35. The lower end of the tube 34 projects through and is carried by the bottom wall 36 of the tank or receptacle wherein the bell reciprocates, said tank or receptacle containing water for sealing the lower end of the bell. The base 33 constitutes a condensation chamber wherein water-vapor mingled with the gas may condense. To prevent the water from rising to an undesirable height in the condensation chamber and sealing the gas tube and vent pipe, the base is provided with an outlet 37 communicating with an open-topped receptacle 38 formed on the outside of the base. The upper portion or holder proper is conveniently supported on the base by resting on the flanges 39 and is firmly secured to said base by means of a rod 40 which extends through the bottom 36 and the bottom 41 of the base, being secured in place by means of nuts 42, 43 threaded onto said rod above and below the bottom 36 and 41 respectively. The bottom 41 tapers upwardly or is conical to permit the lower end of the rod to clear the floor or other support for the base.

44 designates a vent pipe, which projects upwardly into a guide tube 45 carried by the bell. The lower end of this tube communicates with the space between the bottom 36 and the top of the water in the condensation chamber. 46 designates a lateral branch projecting through the wall of the casing 33, whence it may lead to any desired point of discharge outside of the apartment in which the apparatus is located. To prevent any undue accumulation of gas in the bell from elevating the same to a height to unseal the bottom thereof, vent openings 47 are provided in the guide tube 45 carried by the bell thereby, when the bell is elevated a sufficient distance to bring said openings above the level of the water in the tank, gas may pass into the tube 45 and into the open upper end of pipe 44, whence it passes to the point of discharge.

The holder is provided with the usual house pipe 48, the lower end of which projects downwardly nearly to the bottom of the condensation chamber, providing means for receiving any water or condensation that may be in the gas. A lateral branch 49 of the pipe 48 conducts the gas to the points of use. The holder is provided with an arm 50, the lower end of which carries a projection 51 for engaging the finger 14 and operating the valve rod when the gas within the holder is reduced to a predetermined extent. When the holder descends, this lug engages the finger 14 and operates the valve rod, lifting the valve 18. If any material quantity of carbide be present in the auxiliary receptacle 26, sufficient gas will be generated to elevate the holder without operating the valve 19. Should, however, the receptacle 26 be empty or nearly

empty, as is ordinarily the case, the holder will continue to descend and the projection 51 will engage the bottom of the valve 19, lifting the same and supplying carbide from the main receptacle into the auxiliary receptacle and thence into the generator. Should the bell descend until the projection 51 passes below the finger 14, the manner of pivoting said finger will enable the projection to pass thereby on the upward movement of the holder without affecting the position of the valve rod.

The purpose of the lower receptacle 26 and valve 18 is to provide a safety cut-off for the carbide in the event that the valve 19 should fail to be seated as the rod 17 descends. It may happen that some lumps of carbide will be interposed between the bottom of the valve 19 and the adjacent surface of the inclined bottom 24, with the result that carbide will continue to flow from the receptacle 22. The provision of the auxiliary receptacle 26 and the valve 18 insures the cutting off of the carbide from the generator even should the valve 19 prove ineffective.

The valve 19 is the principal valve for controlling the supply of carbide to the generator, while the valve 18 is an auxiliary valve in the auxiliary receptacle 26, the main purpose of which is to act as a safety cut-off, should the valve 19 be held off its seat, as by a lump of carbide catching under the lower edge thereof. The range of movement of the rod 11, when operated by the bell, is such as to nearly always lift the valve 19 when the bell descends, and this valve will nearly always be so lifted, an exception to the rule occurring when it has been held up by a lump or lumps of carbide. When so held up, some finely divided carbide feeds into the receptacle 26, whence it drops into the generator, when the valve rod is lifted. If there is insufficient carbide in 26 to generate gas in sufficient quantities to lift the bell 35 a distance to carry 51 above 14, the further descent of the bell will cause the valve 19 to be lifted and the principal supply of carbide will be turned onto the generator. When 19 fails to seat, for the reasons above stated, the valve 18 will seat, as the quantity of carbide which escapes from below 19 will be relatively small and will be in a finely divided condition.

To prevent the escape of gas into the apartment at the time of filling the carbide tank 22, I provide means for automatically venting the gas from within the upper portion of the generator and casing 6, by the act of filling the receptacle. 52 designates a branch pipe leading from the pipe 2 through the wall of the base or condensation chamber 33, above the level of the water therein and outside of the receptacle 32.

This pipe is provided with a valve 53 having an operating handle 54 which extends across the handle 55 by which the valve 56 of the outlet 8 is operated. This handle is 5 connected by a chain 57 with an arm 58 projecting from a cover 59 which is hinged to the top of the tank 22 and covers the closure 60 thereon. This closure 60 is of a familiar type including a bail 61, cover plate 10 62, and a threaded stem 63, extending through said bail and threaded thereinto, with its lower end engaging the cover plate 62, whereby the cover plate may be firmly forced down on top of the receptacle. Before 15 removing the cover, it will be necessary to swing back the hood 59. In so doing, the arm 58 will lift the handle 54, open the valve 53 and provide a path of least resistance for the flow of the gas in the upper 20 portion of the generator and casing 6 through the branch 46 of the vent pipe.

The advantage of my construction hereinbefore described will be apparent. By the provision of the auxiliary receptacle 26, 25 excessive feed of carbide to the tank is prevented. Furthermore, by the automatic venting of the generator, the annoyance and danger incident to liberating the gas into the apartment where the generator is located 30 at the time of filling the tank with carbide are obviated. Extending the branch 11 of the valve rod through the opening in the bottom of the tube 9 secures a liquid seal for the opening through which said 35 branch extends and dispenses with the necessity for packing the same. The constant circulation of water through the tube 9 prevents the accumulation of calcium hydrate on the rod 11 and the clogging of the movements of the rod through the tube 9. At 40 the same time, by using the lateral spout and closing the lower end of the tube around the rod, there can be no leakage of gas through the tube 9, should the carbide get 45 under the lower end of said tube, the tube acting as a combined seal and water supply tube.

In operation, carbide drops from auxiliary receptacle 26, through openings 28 and 5 into the water within generator 1. The usual chemical reaction takes place and the acetylene gas evolved rises to the top of the generator housing and is conducted through pipe 2 to receptacle 32 where it is washed 55 as previously described. The washed gas then rises through pipe 34 to bell 35 and is stored until required for use, whereupon it is withdrawn through pipes 48 and 49. As the gas is withdrawn from the bell it 60 descends and projection 51 engages finger 14 to operate valves 18 and 19 to supply another charge of carbide to the generator as previously set forth.

While I have necessarily described my invention in detail, it will be evident that such

details may be departed from more or less without avoiding the spirit of my invention and I do not propose to be limited to such details except as they may be positively included in the claims hereto annexed. 70

Having thus described my invention what I claim is:

1. In an acetylene apparatus, the combination of a generator, a main carbide receptacle having a downwardly inclined bottom with a central outlet, a valve above the inclined bottom and controlling the outlet, an auxiliary receptacle below the former receptacle and having an inclined bottom with a central outlet therethrough, a valve 75 above the inclined bottom of the latter receptacle and controlling the outlet, a rod extending through said valves, the latter valve being connected to the rod and the first-mentioned valve being loose on said 80 rod, and a projection on said rod intermediate said valve and adapted to engage and lift the first-mentioned valve when the rod has been moved a predetermined distance, 85 substantially as specified. 90

2. In an acetylene apparatus, the combination of a generator, a carbide-supplying device therefor comprising superposed receptacles, each being provided with a downwardly inclined bottom having a central 95 outlet, a conical valve in each of said receptacles, the base of each of said valves coating with the inclined bottom of its receptacle and controlling the supply of carbide through the outlet, a common valve- 100 operating rod for both of said valves, said rod being rigidly connected to one of said valves, the other of said valves being slidably mounted on said rod, and means on said rod interposed between said valves and 105 adapted to engage the slidably mounted valve when the rigidly mounted valve has been moved a predetermined distance by said rod, substantially as specified. 110

3. In an acetylene apparatus, the combination of a generator, a main carbide receptacle having a downwardly inclined bottom provided with a central outlet, an auxiliary carbide receptacle, the latter receptacle having an inclined bottom provided with 115 a central outlet, a valve above the inclined bottom of each of said receptacles and controlling the outlets thereof, a rod common to both said valves and fixed to the lower valve, the upper valve being slidably mounted on said rod, a lever connected with said rod, a gas holder, means carried by said holder for engaging said lever to move said rod by the depression of the holder, and a valve-engaging device on said rod adapted 120 to engage the valve in the upper receptacle and lift the same when the valve in the lower receptacle has been elevated a predetermined distance. 125

4. In an acetylene apparatus, the com- 130

bination of a generator and a water supply tank thereabove, a carbide receptacle above said generator, a downwardly projecting tube communicating with said water receptacle and projecting into the generator, a valve for controlling the supply of carbide from the carbide receptacle, a valve rod operatively connected with said valve and comprising two branches, one of said

10 branches extending upwardly through said tube and said tube forming at the bottom

thereof a close joint with said rod, an operating arm connected with the upwardly extending branch of said rod, and a gas holder having a projection adapted to engage said arm, said tube being provided above such joint with a lateral outlet to supply the generator with water from the supply tank.

In testimony whereof, I hereunto affix my signature.

JOHN HARRIS.
